UNITED STATES PATENT OFFICE.

ORVILLE M. MORSE, OF JACKSON, MICHIGAN.

SEPARATOR.

SPECIFICATION forming part of Letters Patent No. 555,874, dated March 3, 1896.

Application filed July 27, 1894. Serial No. 518,742. (No model.)

To all whom it may concern:

Be it known that I, ORVILLE M. MORSE, a citizen of the United States, residing at Jackson, in the county of Jackson and State of Michigan, have invented certain new and useful Improvements in Separators, of which the following is a specification, reference being had therein to the accompanying drawings.

The invention consists in an apparatus for separating or purifying materials especially intended for use with grain or grain products, and in which the material is delivered into an air-current where it is graded or separated by centrifugal force, the air delivered from the machine being, if desired, purified and returned to the separator.

The invention further consists in the construction, arrangement and combination of the various parts, all as more fully herein-after described.

In the drawings, Figure 1 is a vertical central section through a machine adapted to carry out my method and embodying my improvements. Fig. 2 is a cross-section through the top of the dust-collector or air-purifier. Fig. 3 is a top plan view of the bottom of the centrifugal separator-casing. Figs. 4, 5, and 6 are vertical sections through machines embodying my invention, showing modifications from the construction shown in Fig. 1.

In the previous state of the art separating-machines have been constructed embodying a casing, preferably tapering, having a fan near the bottom, an annular bottom plate, a discharge-passage through the bottom for the cleaned material, a dust-outlet at the top, and devices for feeding the material against the side of the casing above the bottom. In these devices the air circulation is spirally upward from the bottom of the casing around the side and downwardly in the center or vortex. Some of the dust will be thrown by centrifugal force against the wall of the casing and will gradually ascend, finding exit through the dust-outlet at the top, but the light impalpable dust or "fluff" which is carried by the air is returned again and again to the bottom of the casing with the air, and more or less of it will be carried with the cleaned material. In other words, there is an interior air-circuit in the separator-casing in which the light dust is carried.

My improvement embodies the use of a centrifugal separator in which the air is constantly renewed, passing through the machine, carrying the light dust with it, and yet effecting a perfect separation by centrifugal action of the material, which may be graded by cut-offs in the wall of the casing.

I have shown my separator connected with and combined with a dust-collector such as is described and shown in United States Patent No. 516,171, and while I deem this the preferable form of dust-collector to be used any other means of purifying the air of its dust may be employed.

A is a suitable frame for supporting the various parts of the mechanism. In this frame is the circular casing B, preferably tapering from its base to its top. At the lower edge of this casing is an inwardly-extending ring B', which forms the bottom or a portion thereof. This bottom ring may be supplemented by an inwardly-extending ring B'', preferably of sheet metal, secured to the top of the inner edge of the ring B' and extending inwardly, leaving the central portion open. This bottom ring is provided with apertures to feed the material from the separator-casing B into the hopper C beneath. These may be vertical apertures, as shown in Figs. 4, 5, and 6, or, as shown in Figs. 1 and 3, consisting of tangential grooves B³, formed in the upper face of the ring B', extending from near the casing to the inner edge of the ring, and there discharging into the hopper C. This hopper has a spout C' for the cleaned material, preferably provided with a valve C².

In Fig. 1 I have shown a casing D around the casing C to form an annular air-chamber D' communicating into the hopper over the top to make an even distribution of the incoming air all around the casing, D² being the air-supply trunk at the bottom of the chamber D'. Instead of this construction, however, the air-trunk D² may lead directly to the bottom of the hopper C, as shown in Figs. 4 and 5. The construction shown in Fig. 1 is preferable, however, for reasons which I will hereinafter explain.

At the top of the casing B is an expansion-chamber F, formed by the casing F', which is larger than the top of the casing B and forms outside that casing around the top the dust-

channel F^2 , which may connect into a discharge-chute G , Fig. 5, or into the trunk G' , which connects into the expansion-chamber H beside the dust-collector. This expansion chamber has a spout H' for discharging the dust settling therein. The top of this chamber connects with the eye of the fan I , the discharge of which communicates into the chamber I' of the dust-collector. The bottom 10 of this chamber is apertured, and depending therefrom around the apertures are the textile tubes J , secured to the apertured head J' at their lower ends, below which is the hopper J^2 , the construction of this dust-collector 15 being substantially as described and shown in the before-mentioned patent, No. 516,171.

The chamber L around the tubes I have shown connected by the trunk L' with the trunk D^2 leading to the separator. The chamber L may be inclosed by suitable panels M , or these may be omitted, so that the air from the room may freely enter into the trunk D^2 .

O is a shaft passing through the casing B and driven from any suitable source of power.

25 Near the lower end of the casing B it is provided with a fan. In Figs. 1, 4, and 5 I have shown this fan formed simply of radial arms

a. In Figs. 4 and 6 I have shown the usual fan-blades. This fan is covered with a plate 30 or cover b extending nearly to the casing B , but leaving an annular air-passage c between the fan and casing B . This cover is substantially a diaphragm serving to form the restricted annular passage c .

35 d is a spreader-plate on the shaft above the plate b , and e is a feed-spout around the shaft and adapted to deliver the material on the plate d .

40 f is an arm extending from the fan and having a scraper-blade h in the dust-chamber F^2 .

Q is a cut-off in the wall of the separator-casing, extending preferably from near the top of the cover b some distance up the casing and controlled by a suitable slide Q' .

45 I may use, and preferably do, two slides Q' , one at top and one at the bottom of the cut-off, so that I can control the size as well as the location of the cut-off aperture. This preferably connects into spout Q^2 , which has 50 a connection Q^3 into the top of the casing.

The operation of the device is as follows: Motion is imparted to the shaft O , which rapidly turns the fan and its disk or cover and the distributing-plate d . The material—such 55 as middlings—is fed through the spout e and will be fed over the disk b and thrown against the side of the casing across the rising air-current which will pass through the passage c .

The heavy material will fall through this air-current upon the ring B' , and from thence will 60 pass through the grooves B^3 to the inner edge of the ring, and in falling therefrom will be subjected to an air separation by the horizontal current passing from the chamber D' 65 to the inner edge of the ring B^2 , Fig. 1. The cleaned material will fall into the hopper C

and be spouted from the spout C' . This separation by the horizontal air-current is desirable, but not necessary, and the material may pass directly through vertical apertures into 70 the hopper C , as shown in Figs. 4, 5 and 6.

I prefer to employ ribs P in the hopper C , as shown in Figs. 5 and 6, to prevent the whirling of the air therein.

The material which is heavy enough to overcome the upward motion of the air will fall. That which is not heavy enough to fall and not light enough to go out will either follow the wall until it is broken up fine enough to ascend or until a number of particles adhere 80 together and then fall; or, if the cut-off Q is opened, it may be graded by opening this cut-off at different points. The lighter dust will be suspended in the air and carried with it and will pass out with the air-current through 85 the trunk G' into the expansion-chamber H , in which the heavier particles thereof may drop, the bulk of the dust going with the air-current to the fan I and into the dust-collector, where the air will be purified, passing through 90 the textile tubes L into the return-trunk L' or into the room, the dust being collected in the hopper J^2 .

The fan I is of considerably less power than the fan in the casing B , so as to maintain a 95 pressure in that casing, but prevents largely, if not entirely, the interior circulation in the casing B . Thus it will be seen that the air will be drawn in at the bottom of the separator-casing, be driven spirally upwardly therein, 100 carrying with it the heavy dust impelled by centrifugal force against the wall of the casing, through which it may be removed, and the lighter dust suspended in the air-current and carried off therewith, thus purifying the material of its dust of all kinds and delivering it rapidly at the bottom of the machine.

I have found that flour as it comes from the rolls may be fed into my machine and it will separate the fluff and heavier dirt or dust 110 particles from it.

I can largely control the degree of separation by the speed or capacity of the two fans, and I may omit the fan I , as shown in Fig. 6, and still effect the desired separation, though 115 I deem the fan I desirable.

As in Fig. 5, part of the air-current may pass centrally through the fan, beneath the plate d , which central current will pass through the material falling from that plate 120 and carry such dust as it may pick up through the separator-chamber to the dust-collector.

What I claim as my invention is—

1. The combination of a casing having air inlet and exit at opposite ends and a cut-off 125 opening in the side; devices for producing a spiral movement of the air within the casing, and a feed for delivering the material into the air-current, substantially as described.

2. The combination of a casing having an 130 inlet and exit at opposite ends and a cut-off opening in its side, a partially-closed bottom,

a fan near the lower end, an open top, and a feed for delivering the material into air-current in the casing, substantially as described.

3. The combination of a tapering centrifugal separating-casing having an exit at its upper end, and a reduced central inlet at its lower end, a fan near the bottom having an imperforate cover extending to near the side of the casing, and a feed for delivering the material into the casing, substantially as described.

4. The combination of a tapering centrifugal separating-casing having a free exit at the top, an annular bottom forming a central air-inlet a fan above the bottom adapted to produce a positive spiral air circulation from bottom through the top, a covering for the fan, a central feed-tube for delivering the material upon the fan-covering, substantially as described.

5. In a centrifugal separator, the combination of the casing, open at each end for ingress and egress of the air-current, devices for producing a spiral movement of the air from the inlet to the exit, a diaphragm serving to form a restricted air-passage between the same and the wall of the separator-chamber, and a feed for delivering the material into or across this passage.

6. In a centrifugal separator having inlet and exit at opposite ends of the separator-casing, and devices for producing a spiral movement of the air from the inlet to the exit, a diaphragm serving to form a marginal restricted air-passage around the wall of the separator-chamber, a feed for delivering the material into or across this passage and an auxiliary fan for drawing the dust-laden air from the exit of the separator-casing.

7. The combination with a centrifugal separator-casing, having an air-inlet at the bottom and a free air-exit at the top, of a diaphragm therein forming a narrow annular marginal passage at the inlet thereof, a fan below the diaphragm, a feed for the material into the casing above the diaphragm, and a fan having its suction side connected to the exit from the separator-casing, substantially as described.

8. The combination of the tapering centrifugal separating-casing, having a free exit at the small end, of a ring-shaped bottom, an imperforate diaphragm above the bottom to form an annular air-inlet between the same and casing, and a fan beneath the diaphragm, a feed above the diaphragm and discharge-apertures through the ring-shaped bottom, substantially as described.

9. In a centrifugal separator the combination of the casing, means for creating a spiral air-current therethrough, the ring-shaped bottom, having the tangential feed-grooves C' therein, and a feed-spout into the casing, substantially as described.

10. In a centrifugal separator the combination of the casing, devices for producing a spiral movement of the air therethrough, the

ring-shaped bottom B' having the grooves B³, and the ring B² extending inwardly from the ring B' on top thereof, substantially as described.

11. The combination of a centrifugal separator having air inlet and exit at opposite ends, devices for producing a spiral movement of the air under pressure from the inlet to the outlet to thereby effect a centrifugal separation, and a fan having its suction side connected to the said outlet and its discharge side to a dust-collector, substantially as described.

12. The combination of a centrifugal separator, having air inlet and exit at opposite ends, devices for producing a spiral movement of the air from the inlet to the outlet to thereby effect a centrifugal separation, a fan having its suction side connected to the outlet and the discharge to a dust-collector, and a trunk connecting the inlet to the separator-chamber with the purified-air chamber of the dust-collector, substantially as described.

13. In a centrifugal separator of the kind described, comprising a tapering casing having a free air-inlet at the bottom, and a free air-exit at the top, devices for imparting a spiral movement of the air through the casing having a cut-off opening in the side below the air-exit, and gates adapted to adjust the size or height of the cut-off opening, substantially as described.

14. In a centrifugal separator, the combination of a casing having an inlet at the bottom, and an exit at the top, devices for producing a spiral movement of the air from the inlet to the exit, an expansion-chamber into which the exit leads, having an exit for the dust-laden air, substantially as described.

15. In a centrifugal separator, the combination of an upwardly and inwardly tapering casing, having an inlet at the bottom and an exit at the top, devices for producing a spiral movement of the air from the bottom out through the top, an expansion-chamber around the top, and a fan having its suction side connected to said expansion-chamber, substantially as described.

16. The combination with the tapering centrifugal separator-casing, having a free air-exit at the upper end, an expansion-chamber into which said exit leads, and devices for positively removing the material from such settling-chamber, substantially as described.

17. The combination with the tapering centrifugal separator-casing having an exit at the top, and its fan adapted to produce a through spiral air circulation, an annular expansion-chamber around the top of the separator-chamber, and a scraper-blade for removing the material from such settling-chamber, substantially as described.

18. The combination with the centrifugal separator-casing having an inlet at the bottom and an exit at or near the top, of an expansion-chamber into which the exit leads, devices for removing the material from the bot-

tom of the expansion-chamber, and a fan for drawing the dust-laden air from said chamber, substantially as described.

19. In a centrifugal separator, the combination of the tapering casing, open at top and bottom so as to permit ingress and egress of an air-current, devices for producing a spiral air-current from the inlet to the exit on the wall of the casing, a diaphragm or partition

forming a restricted air-passage in the air-current and a feed for delivering the material into the air-current.

In testimony whereof I affix my signature in presence of two witnesses.

ORVILLE M. MORSE.
